UNITED STATES PATENT OFFICE.

GEORGE B. GEISER, OF PHILADELPHIA, PENNSYLVANIA, ASSIGNOR TO BERGER BROTHERS COMPANY, OF PHILADELPHIA, PENNSYLVANIA, A CORPORATION OF PENNSYLVANIA.

GUTTER-HANGER CIRCLE.

Application filed November 12, 1925. Serial No. 68,502.

My invention relates to an improvement in gutter hanger circles.

Heretofore gutter hanger circles, used, as is well known, for supporting gutters on the roofs of buildings, have been formed by casting and pressed from sheet metal and such circles have proved satisfactory. However, it has been suggested that circles be formed by bending bars of metal of U or channel cross-section in the desired circle form and effect the formation of the gutter bead hook and gutter strap hook by bending over extensions of one of the sides or flanges of the channel bar. Such a structure forms the subject-matter of an application for patent filed by me July 1st, 1925, Serial No. 40,720, and while it has been found to be of superior efficiency, it is open to some objection in that the bead and strap hooks, due to the formation of bending, are liable to break off if subjected to any great strain.

Now it is the object of my present invention to provide an improved circle formed from a bar of U or channel section, and more particularly one in which the bead and strap hooks are formed in such a manner as to insure against breakage under any strain likely to be put upon it and one in which the channel structure of the bar from which the circle is formed is retained, thus giving a circle of maximum strength.

Having now indicated, in a general way, the nature and purpose of my invention, I will proceed to a detailed description thereof, with reference to the accompanying drawings, in which is illustrated a preferred embodiment, and in which—

Fig. 1 illustrates a gutter hanger circle embodying my invention, shown in relation to a supporting shank indicated by dotted lines.

Fig. 2 is a detail view of a portion of the circle.

Fig. 3 is a view of a portion of the circle taken at right angles to its extension.

The circle is formed from a bar of U or channel shape and comprises a supporting web *a*, a gutter seat *b* and a bottom flange *c*, formed respectively by the web and flanges of the bar from which the circle is formed.

Adjacent one end the circle is extended vertically and a rib *d* formed, by distortion of the web portion, for engagement within the shank *e*, which is of channel section.

55 The outer and inner flanges *c* and *b* extend

parallel with the rib *d*, and the rib and web of the shank are provided with a series of holes *f* to enable the circle to be secured to the shank by means of a bolt and nut *g*.

The gutter supporting flange *b* extends parallel with the flange *c* and beyond the end of the vertically extending end of the circle, the extended portion being formed by cutting away the web and outer flange. Adjacent the juncture of the end of the web with the base of the extended portion of the flange *b*, the end of the web is notched as at *h*, which permits the extended portion of the flange *b* to be bent over to form a gutter bead hook *i*, without putting undue tension on the upper surface of the metal forming the hook.

Adjacent the other or free end of the circle is formed a gutter strap hook *j*, the formation of the hook being effected by cutting out a section of the outer flange *c* and of the web *a*. The hook *j* when formed consists, as will be observed, of a section of the lower flange *c* joined to the gutter supporting seat by a section of the web *a*.

The strap hook as described requires for its production no deformation of the material of which the circle is formed and neither the hook nor the material connecting it with the circle proper is under any initial strain and therefore has a maximum resistance to strain put upon it.

Further, the gutter bead hook shown is of greatly increased efficiency in that the notch *h* in the web at the base of the hook enables the hook to be bent without undue strain or tension on the metal of its upper surface.

The circle as a whole is possessed of maximum strength, since, as will be observed, the outer flange as well as the seat extend throughout both the free or gutter engaging portion of the circle and that portion which is engaged with the circle supporting shank, thus insuring strength at the point of greatest strain when the circle extends from the circle support.

Having now fully described by invention, what I claim and desire to protect by Letters Patent is:

A gutter hanger circle comprising a curved flange forming a gutter seat, a supporting web extending outwardly from the flange, and a gutter engaging hook formed by an inwardly bent portion of the flange extending beyond an end of the supporting

web, said end of the supporting web being notched at a point slightly spaced from the flange, whereby subsequent bending of the flange, and the portion of the web between the notch and the flange produces a gutter engaging hook reinforced at its bend by an inwardly extend-

ing web member integral with the supporting web.

In testimony of which invention, I have ¹⁰ hereunto set my hand, at Philadelphia, Pennsylvania, on this 11th day of November, 1925.

GEORGE B. GEISER.
